CLAIM

The ornamental design for a calf, as shown and described.

DESCRIPTION

FIG. 1 is a perspective view of calf showing my new design;

FIG. 2 is a left side elevational view thereof;

FIG. 3 is a right side elevational view thereof;

FIG. 4 is a bottom view thereof;

FIG. 5 is a front elevational view thereof;

FIG. 6 is a rear elevational view thereof; and,

FIG. 7 is a top plan view thereof.

The claimed calf is as a soft toy, as an eiderdown or as a pillow.
